(57) **CLAIM**

The ornamental design for a prying tool for use while standing, as shown and described.

DESCRIPTION

FIG. 1 is a perspective view of a prying tool for use while standing showing my new design;

FIG. 2 shows a right side view thereof;

FIG. 3 shows a left view thereof;

FIG. 4 shows a front view thereof;

FIG. 5 shows a rear view thereof;

FIG. 6 shows a top plan view thereof;

FIG. 7 is a bottom plan view thereof; and,

FIG. 8 is an enlarged perspective view thereof.

The shade lines in the Figures show contour and not surface ornamentation.

The broken lines shown in the Figures show portions of the prying tool for use while standing which form no part of the claimed design.
